DISPLAY RACK

Teresa Cummings, Buffalo, N. Y.

Application January 23, 1947, Serial No. 723,722

5 Claims. (Cl. 211—130)

1

This invention relates to certain new and useful improvements in a portable display rack or stand for domestic and commercial purposes.

It has for one of its objects to provide a stand of this character which is simple, compact and inexpensive in construction, and which is designed to store or display a maximum amount of articles or merchandise in a minimum of floor space and in an effective and readily accessible manner.

Another object of the invention is to provide a portable and light weight display rack which is so constructed as to be compactly foldable when not in use and which embodies display trays or shelves having novel means for effectually supporting them as well as for automatically governing their movements to a display or non-display position when the stand is unfolded for use or collapsed for storage purposes.

Other features of the invention reside in the construction and arrangement of parts herein-after described and particularly pointed out in the appended claims.

In the accompanying drawings: Figure 1 is a perspective view of the display rack embodying my invention. Figure 2 is an end view thereof. Figure 3 is a cross section taken on line 3—3, Figure 2.

Similar characters of reference indicate the corresponding parts throughout the several views.

Referring now to the drawings, showing the preferred embodiment of my invention, 10, 10 indicates generally a pair of foldable end frames or standards between which display racks or shelves 11 are suspended in a horizontal position to assume an operative display position or an upwardly-tilted non-display position when the standards are folded or collapsed for storage or shipping purposes. Each of the standards includes front and rear legs 12 and 13, respectively, pivoted at their upper ends to a horizontal tie bar or rod 14 which may also serve as a support for pendant hangers or holders 15 for detachably supporting desired articles thereon. The rear standard-legs 13 may be provided with casters 16 for facilitating the movement of the rack from one place to another. The trays are substantially rectangular in shape and may be of different widths and depths and partitioned as desired depending upon the specific use to which the rack is to be put.

The legs of the standards 10 are held in their distended operative or display position by a plurality of brace links or arms 17, corresponding in number to the trays 11, each having a longitudinal

2

slot 18 intermediate its ends and being pivoted at its rear end, as indicated at 19, to the rear leg 13 for vertically swinging movement relative thereto. Applied to the front legs are adjusting, wing-nut type screws 20 or like fasteners which extend through the slotted links and serve to adjustably retain the standard-legs in any desired distended position. In all positions of adjustment, however, the front ends of the brace links extend somewhat beyond and forwardly of the front legs 12 for a purpose presently to appear.

Each tray 11 is pivotally suspended at its opposite ends and adjacent the rear side thereof to the companion front legs of the standards 10, as indicated at 21 to swing vertically to and from an operative display position. Forwardly of its suspension pivot 21, each tray is pivotally supported at its front end at 22 to the front end of the companion brace-link 17 and for this purpose the pivot thereof engages the front end of the link-slot 18. By this construction the trays are not only effectually held in a set display position upon spreading the standard-legs and clamping the respective adjusting screws 20, but when it is desired to fold the rack for storing or otherwise, as the legs are collapsed the respective trays swing upwardly with the links 18 to make for a compact unit. Furthermore, the brace-links function as common bracers and supports for the standard-legs and trays, respectively.

I claim as my invention:

1. A display stand of the character described, comprising a pair of standards each including members pivoted at their upper ends to assume an extended supporting position or a contracted folded position, trays disposed horizontally between said standards and pivoted adjacent their rear ends to one of the companion standard members, and brace links, each pivotally connected at one end to the other standard members and at their opposite ends to a companion tray forwardly of its pivot and movably joined intermediate its ends to the tray-pivoted standard members.

2. A display stand of the character described, comprising a pair of standards each including foldable front and rear legs pivotally joined at their upper ends, a plurality of brace links pivoted at one end to the rear legs and each having a displaceable connection intermediate its ends with the companion front leg, and a plurality of trays disposed horizontally between said standards and pivoted adjacent their rear ends to the front legs of said standards and pivotally joined ad-

adjacent their front ends to the opposing ends of the companion brace links.

3. A display stand of the character described, comprising a pair of standards each including foldable front and rear legs pivotally joined at their upper ends, a plurality of trays disposed horizontally between said standards and pivoted to the front legs thereof to swing vertically relatively thereto, and brace means pivotally connecting said trays with the rear legs of said standards and each having an adjustable connection to the front legs of the standards.

4. A display stand of the character described, comprising a pair of standards each including, foldable front and rear legs pivotally joined at their upper ends, brace-links pivotally joined at one end to the rear standard legs and having a longitudinal displaceable connection with the companion front legs to effect a relative swinging of said links in response to a folding or unfolding movement of the standards, and trays suspended between said standards and each pivoted adjacent its rear end to the front standard legs and at its front end to the free end of the companion brace-link.

5. A display stand of the character described, comprising a pair of standards each including foldable front and rear legs pivotally joined at their upper ends, brace-links pivotally joined at

one end to the rear standard legs and having a longitudinal displaceable connection with the companion front legs to effect a relative swinging of said links in response to a folding or unfolding movement of the standards, means correlated with said front legs and the displaceable connection of said brace-links for adjustably clamping the latter in a set position, and trays suspended between said standards and each pivoted adjacent its rear end to the front standard legs and at its front end to the free ends of the companion brace-link.
